(57) **CLAIM**

The ornamental design for a data accessing device, as shown and described.

DESCRIPTION

FIG. 1 is a perspective view of a data accessing device of the claimed design;

FIG. 2 is a front elevation view of FIG. 1;

FIG. 3 is a rear elevation view of FIG. 1;

FIG. 4 is an enlarged left side elevation view of FIG. 1;

FIG. 5 is an enlarged right side elevation view of FIG. 1;

FIG. 6 is a top plan view of FIG. 1;

FIG. 7 is a bottom plan view of FIG. 1;

FIG. 8 is a perspective view of the data accessing device of FIG. 1, shown in an alternate configuration; and,

FIG. 9 is another perspective view of the data accessing device of FIG. 1, shown in an alternate configuration. The broken lines in the drawings depict portions of the data accessing device that form no part of the claimed design.
